UNITED STATES PATENT OFFICE.

MOTOICHI FURUYA, OF NEW YORK, N. Y.

SPRING-HINGE.

1,076,568.

Specification of Letters Patent.

Patented Oct. 21, 1913.

Application filed June 13, 1913. Serial No. 773,416.

To all whom it may concern:

Be it known that I, MOTOICHI FURUYA, a subject of the Mikado of Japan, and a resident of the city of New York, borough of 5 Manhattan, in the county and State of New York, have invented a new and Improved Spring-Hinge, of which the following is a full, clear, and exact description.

This invention relates to improvements 10 in spring hinges and has for an object to provide a spring hinge with a pair of pivotally connected leaves, and a spring structure acting on the leaves normally for maintaining the same in a certain position, the 15 hinge and the spring having associated therewith a lock for locking the spring against operation in one direction when the leaves have been opened to a certain extent in order to allow the leaves to move back 20 and forth pivotally freely within certain limits.

A still further object of the invention is to provide a spring hinge for doors which will permit the doors to be opened to a certain extent and allow the doors to remain 25 open while normally closing the doors when not opened to the predetermined extent mentioned.

A practical embodiment of the invention 30 is represented in the accompanying drawings forming a part of this specification in which similar characters of reference indicate corresponding parts in all the views.

Figure 1 is a side view of a door to which 35 is connected a spring hinge disclosing an embodiment of the invention; Fig. 2 is a perspective view of one of the leaves and its corresponding barrels; Fig. 3 is a side view of the pintle, springs, and associated parts; 40 Fig. 4 is a perspective view of the opposite leaf to that shown in Fig. 3, its corresponding barrel being connected therewith; Fig. 5 is a longitudinal vertical section through the barrel of the hinge with the hinge, spring 45 and associated parts assembled; Fig. 6 is a fragmentary sectional view similar to Fig. 5, except that the various parts are shown in different positions; and Fig. 7 is a detail fragmentary perspective view of the locking 50 member.

Referring to the accompanying drawings by numerals, 1 indicates a door casing of any kind, and 2 a screen door. In mounting the screen door 2 a hinge 4 of any desired 55 structure may be used, and in connection therewith a spring hinge 5 embodying the

invention may also be used. The hinge 5 is provided with leaves 6 and 7, the leaf 6 having barrel portions 8 and 9, and leaf 7 having barrel portions 10 and 11. These 60 barrel portions are designed to properly interlock and accommodate pintle members 12 and 13. Pintle member 13 carries a sleeve 14 which is rigidly secured thereto by any desired means, as for instance a pin or rivet, 65 and is formed with a notch 15 whereby an abutment 16 is provided. The projection or abutment 17 formed on the tubular portion 9, is designed to co-act with abutment 16 in order to allow spring 18 which is rigidly 70 secured to pintle member 13, to act on leaf 6 for moving the same to a closed position. The pintle member 12 is secured rigidly to the barrel member 10 by any desired means, as for instance a pin 19. In assembling the 75 device, the spring 18 is compressed sufficiently for continually giving member 14 a tendency to press against projection 17 for holding the leaf 6 in a closed position. Arranged in the barrel 11 is a locking member 80 20 which has an operating handle 21 extending through a suitable slot 22 in the barrel portion 11. This locking member is provided with a notch 23 which results in a projection 24 designed to act against the projection 25 (Fig. 3) at the lower end of pintle member 13. A spring 26 continually acts on locking member 20 for giving the same a tendency to move upwardly or into the notch 27 opposite the projection 25. As pin 90 21 is in slot 22, locking member 20 cannot rotate so that when locking member 20 has the projection 24 fitting into notch 27, the pintle member 13 cannot rotate, but leaf 6 may be moved freely in one direction but 95 cannot be moved in the opposite direction by reason of shoulder 17 striking against abutment 16. In arranging the locking member 20, the same is arranged in the barrel portion 11 so as to engage the projection 25 100 on pintle member 13 when leaf 6 is at substantially right angles to the leaf 7. In this way when the door 2 is moved through ninety degrees of a circle, the same will remain open until pin 21 has been pressed, 105 which will lower locking member 20 and allow member 13 to rotate until shoulder or abutment 16 engages the projection 17.

Having thus described my invention I claim as new and desire to secure by Letters 110 Patent:—

1. In a spring hinge of the class described,

a pair of leaves provided with interlocking barrel portions, a pintle for said barrel portions divided into an upper section and a lower section, said upper section being secured to the barrel portion of one of said leaves and the lower section of said pintle being freely rotatable, an interlocking projection arranged on said lower section for engaging the leaf not secured to said upper 10 section, an operating spring connecting said upper section and said lower section, whereby when said spring is under tension the leaves will tend to move in opposite directions, a sliding locking member designed 15 to interlock with the lower section of said pintle, and an auxiliary spring acting on said locking member for causing the same to engage and lock said lower section against movement, whereby the leaves may be swung 20 back and forth freely.

2. In a spring hinge of the class described, a pair of leaves, an upper pintle member for connecting said leaves together, a freely rotatable lower pintle member, a stop rigidly 25 connected with said lower pintle member adapted to press against one of said leaves, a spring having its opposite ends secured to said pintle members, said second mentioned pintle members being formed with a projection, a locking member, and means continually tending to move said locking member in the path of movement of said projection.

3. In a spring hinge of the class described, a pair of leaves, each of said leaves being

formed with an upper and a lower barrel 35 member, the lower barrel member on one of said leaves being provided with a projection, an upper pintle member for connecting the upper barrel members of both of said leaves, means for rigidly connecting said upper pintle member with one of said leaves, a lower 40 pintle member, said lower pintle member projecting through the barrel member formed with a projection, a sleeve surrounding 45 said lower pintles formed with a projection designed to interlock with the projection on said barrel member, said lower pintle member being formed with a projection at the lower end thereof, a spring connecting 50 said pintle members, a locking member arranged in one of the lower barrel members, said locking member being formed with a projection designed to be moved into the path of movement of the projection arranged at the bottom of said second men- 55 tioned pintle member, a spring acting on said locking member for continually tending to move the same, and an operating member for moving said locking member out of the path of movement of the projection 60 on said lower pintle member.

In testimony whereof I have signed my name to this specification in the presence of two subscribing witnesses.

MOTOICHI FURUYA.
